UNITED STATES PATENT OFFICE.

JULIUS P. STADERMAN, OF BUFFALO, NEW YORK.

DESIGN FOR A PICTURE-FRAME.

No. 39,372.

Specification for Design.

Patented June 23, 1908.

Application filed April 29, 1908. Serial No. 430,029. Term of patent 3½ years.

To all whom it may concern:

Be it known that I, JULIUS P. STADERMAN, a citizen of the United States, residing at Buffalo, in the county of Erie and State of New York, have invented a new, original, and ornamental Design for Picture-Frames, of which the following is a specification, reference being had to the accompanying drawings, forming part thereof.

Figures 1 and 2 are perspective views of a picture frame viewed from the front and rear thereof respectively and showing my new design.

I claim:

The ornamental design for a picture frame, as shown.

JULIUS P. STADERMAN.
